(57) **CLAIM**

The ornamental design for a carton, as shown and described.

DESCRIPTION

FIG. 1 is a perspective view of the carton embodying my new design;

FIG. 2 is a right side elevation view, the left side elevation view being a mirror image thereof;

FIG. 3 is a top planar view as viewed from the upper left relative to the left side view thereof;

FIG. 4 is a front elevational view thereof;

FIG. 5 is a rear elevational view thereof;

FIG. 6 is a bottom planar view, opposite of the view in FIG. 3; and,

FIG. 7 is a top planar view as viewed from the upper right relative to the left side view thereof.

The broken lines in the drawings represent unclaimed environmental subject matter.
